ATTORNEY

UNITED STATES PATENT OFFICE.

FRED LUX, OF MILMINE, ILLINOIS.

LEAD RING.

Application filed April 13, 1923. Serial No. 631,794.

To all whom it may concern:

Be it known that I, FRED LUX, a citizen of the United States of America, and a resident of Milmine, Illinois, have invented a certain new and useful Improvement in Lead Rings, of which the following is a specification.

This invention relates to the devices for use in leading animals, embodying a simple two-piece jaw device operating on a single pivotal point, and having at one end, two gripping jaws or arms for the purpose of gripping the cartilage of the animal's nose, and at the other end, two control arms or levers which are held in a closed position against two limiting lugs by means of a spring attached to two terminal lugs at the terminal head of said arms or levers, so that the device is always in a closed position except when opened by a slight pressure outward from the center, spreading the arms and opening the jaws for the purpose of placing the device in or removing it from the animal's nose.

A further purpose of this invention is to provide a device of this type with the particular object of eliminating every possible detail and feature of construction which will render the same costly from a manufacturing basis, and at the same time provide a means of leading animals with a device embodying the simplest principle of operation.

In the accompanying drawing, Fig. 1 illustrates an elevation of the face of the device, Fig. 2 an elevation of the side, and Fig. 3 a plan of the bottom without the chain links and spring.

In the drawing the numeral 1 indicates the gripping ends at the extremities of the gripping jaws or arms 2, which operate on the pivotal point 3, by means of the action of the controlling arms or levers 4, which are constantly held in closed position against the limiting lugs 5, by means of the spring 6, which is attached to the terminal lugs 7, at the terminal heads 8. The terminal holes 9, receive the chain links 10, which hold the lead link 11, into which a lead strap

or rope is tied for the purpose of leading the animal.

The gripping ends 1, are rounded at their extremities to avoid abrasion of the cartilage in the animal's nose.

To place the device in position in the animal's nose, the controlling arms or levers 4, are slightly spread, as shown by the dotted lines 12, expanding the spring 6, which, after the gripping jaws or arms 2, are in place in the nose, and the controlling arms 4 or levers are released, contracts, holding the gripping ends 1, securely in place against the cartilage of the nose. The limiting lugs 5 hold the gripping ends 1, apart just enough to permit the necessary pressure to hold the animal firmly, and yet will not allow them to come close enough together to cause unnecessary pressure or injure the cartilage. The amount of pressure on the gripping ends 1, is determined by the size of the spring 6, used in the terminal lugs 7. Once placed in position in the nose, the device will remain in place until removed by the same simple process used in placing it.

I claim,

The combination substantially as described, of two gripping jaws or arms controlled by opposite arms or levers, said jaws and levers being in one piece and duplicate for both sides of the device, operating on a single pivotal point, and being provided with limiting lugs which are held abutting each other by means of a spring attached to terminal lugs at the terminal heads of said arms or levers, said limiting lugs holding apart the gripping ends of said gripping jaws or arms to a distance required for practical use, and governed by said limiting lugs, as and for the purposes herein set forth.

In testimony whereof I have hereto affixed my signature in the presence of two witnesses.

FRED LUX.
